OVERHEAD-ACTING GRILLE

Milton L. Cornell, New York, N. Y., assignor to
 Cornell Iron Works, Inc., Long Island City,
 N. Y., a corporation of New York

Application October 30, 1933, Serial No. 695,794

11 Claims. (Cl. 189—56)

This invention relates to overhead-acting closures or doors, and more particularly to closures in the form of a flexible grille.

A general object of the invention is to provide 5 an overhead-acting closure having improved and advantageous characteristics, especially as to rapidity and economy of manufacture, coupled with considerable strength and security in the protection of openings.

More particular objects of the invention are to 10 provide a closure for doorways, store fronts, windows and the like, comprising a flexible grille which is adapted to be rolled about a horizontal shaft, and having characteristic features 15 ensuring its facile and certain operation as it is being raised and lowered.

Further objects are to provide an overhead-acting flexible grille of attractive appearance, having a secure and conveniently accessible 20 locking means which harmonizes with the rest of the grille.

Other objects of the invention will in part be obvious and will in part appear hereinafter.

The invention accordingly comprises the 25 features of construction, combination of elements, and arrangement of parts, which will be exemplified in the construction hereinafter set forth and the scope of the application of which will be indicated in the claims.

For a fuller understanding of the nature and 30 objects of the invention reference should be had to the following detailed description taken in connection with the accompanying drawings, in which:

Fig. 1 is a fragmentary, contracted, front elevation of a doorway equipped with a grille type closure embodying features of the present invention;

Fig. 2 is a vertical sectional view taken along line 2—2 of Fig. 1;

Fig. 3 is a fragmentary end elevation, taken 35 along line 3—3 of Fig. 4, showing one side of a grille embodying features of the invention, a portion of the appurtenant guideway being broken away more clearly to show the structure;

Fig. 4 is a fragmentary front elevation of a portion of a grille, part of the appurtenant guideway being broken away;

Fig. 5 is a horizontal sectional view taken 40 along line 5—5 of Fig. 4;

Fig. 6 is a perspective view of an end link used in the grille, part thereof being broken away to illustrate its sectional construction;

Fig. 7 is a fragmentary side elevation showing

the upper portion of the end guides for the flexible grille;

Fig. 8 is a fragmentary horizontal sectional view taken substantially along line 8—8 of Fig. 7;

Fig. 9 is a fragmentary front elevation of a portion of a grille, illustrating one form of lock construction;

Fig. 10 is a horizontal sectional view taken along line 10—10 of Fig. 9;

Fig. 11 is a fragmentary front elevation showing another form of locking device;

Fig. 12 is a fragmentary front elevation showing the locking device of Fig. 11 in locked position;

Fig. 13 is a fragmentary end elevation, generally similar to Fig. 3 but showing another form of construction;

Fig. 14 is a fragmentary front elevation showing a portion of the grille illustrated in Fig. 13;

Fig. 15 is a fragmentary perspective view showing details of the construction.

There are many types of buildings, such as 30 garages, warehouses, and the like, wherein the utilization of overhead-acting or rolling doors proves advantageous. These closures, in this country, have usually been made of solid panel or slat construction. In many cases, the use of overhead-acting closures in the form of open-work grilles is desirable, and, indeed, in some parts of Europe, this latter form of closure is prevalent. Previous designs of these grilles have been such as to reduce the extent of their use in this country. This is because such designs have 35 usually required considerable bending and crimping of the rods with consequent time consuming intricate assembly or laborious welding, or have involved methods of holding the links in position which required intricate bracing construction running into excessive costs. In order practically to utilize open-work grilles of this general type in this country, where the scales of compensation are relatively high, it is desirable to provide a grille which can be readily assembled with a minimum amount of labor, preferably by means of machinery. Grilles embodying features of the present invention are thus designed.

Referring more particularly to the drawings, 50 and first to Fig. 1, there is shown a flexible grille adapted, when in unrolled vertical position, to effect closure of a door opening. This grille comprises a series of lateral rods 20 flexibly connected by a plurality of links 21, each provided 55

at its end with perforate eyes 22 through which the lateral rods engage in rotatable relation. These rods and links are preferably made of cylindrical metallic stock, of a suitable size to secure lightness coupled with requisite strength. Stock on the order of $\frac{1}{8}$ inch diameter is satisfactory, although other gauges may be employed as desired. It will be understood that the fragmentary drawing shown in Fig. 1 is considerably contracted, and that in a preferred form of grille the lateral rods 21 may be spaced apart approximately 2 inches while adjacent links between any two rods may be spaced about 7 inches. The links connecting a given rod with that next above it are staggered with respect to those links connecting such rod to the one below, as illustrated. The links 21 are kept from sliding along rods 20 by means of knobs 23 which may be pinched or struck up from the stock of rod 20 after the links have been threaded thereover into their proper position. This operation can be performed with suitable known power machines, and all of the links along a given rod may be rotatably anchored thereon in a single pinching or striking operation.

At their lateral extremities rods 20 are pivotably connected by end links 24 (Figs. 3 to 6). At their ends, these links have eye portions 25 and 26 which are perforate so as rotatably to accommodate the rods, and which are offset from each other with respect to the longitudinal center line of the link, to enable adjacent links to be arranged with their eye portions in overlapping relation, as best illustrated in Fig. 4, while maintaining their body portions in substantial alignment. This central body portion of each link is provided along its forward edge with a V-shaped male rib 27, and has along its rear edge a corresponding V-shaped female groove 28. These end links, when assembled on the rods 20, are prevented from sliding inwardly therealong by knobs 23 similar to those already described, and are confined against outward movement by means of spring clips 29 which are sprung over suitable nicks or notches which may be conveniently provided near the ends of the rods. This construction is subject to readier manufacture than other devices such as cotterpins.

50 The described male and female ribs and grooves 27 and 28 are, when the grille is rolled spirally about a horizontal shaft, adapted to nest within one another, and maintain the several end links and their attached grille parts in proper alignment. A similar arrangement of aligning ribs and grooves is known through my Patent No. 1,579,915 granted April 6, 1926, and no claim is made herein to such ribs and grooves per se, except in so far as they appear in novel combination with pivotal links useful in connection with a flexible open-work grille of the type here contemplated.

55 The end links 24, during their vertical traverse, are respectively confined within side guides 30, located at opposite sides of the grille. These guides are of channel construction, and have their inner side equipped with inturned flanges 31 which serve to confine the links 24 while permitting free vertical movement of the relatively narrow rods 20. The side guides 30 are respectively surrounded and supported at their upper ends by a casting such as that illustrated at 32 (Figs. 7 and 8). Each casting is equipped with flaring wings 33, which are arranged to form a continuation of the guide walls

of side guides 30 and which facilitate the entry and withdrawal of the side links 24 in and out of such guides as the grille is being uncoiled and coiled about its horizontal shaft located at 34. Each casting 32 is provided with an inwardly projecting lug 35, which may be screwed to the casting or cast integrally therewith as desired. This lug 35 acts as a limiting stop to prevent undue upward movement of the grille as it is coiled, acting in conjunction with a rigidifying angle bar 10 36 (Figs. 1 and 2) which may be suitably fastened to the links 21 at the lowermost portion of the grille. Casting 32 is additionally provided with screw or bolt openings to enable it to be attached in the door frame by means of 15 screws 37.

Heretofore it has been customary to lock open-work grilles in closed position by means of a locking device located at its lower extremity. Such locks are not conveniently accessible and are subject to weathering from snow and water. In accordance with the present invention, there is provided a locking device made from stock similar or identical in appearance with the remainder of the stock used in the grille, and conveniently located about waist high when the grille is closed. One such form of device is illustrated in Figs. 1 and 9, and comprises a pair of bolts 38 and 39, which are slidably mounted for lateral movement in especially designed connecting links 40 which, in addition to having the usual eyes 22 at their ends are each provided centrally with an additional perforate eye 41. The inner ends of bolts 38 and 39 are overlapped, as illustrated. Bolt 39 carries rigidly 38 therewith a strap 42 which slidably embraces the adjacent bolt 38 at 43, while bolt 38 likewise carries a strap 44 which slidably embraces bolt 39 at 45. These straps each respectively carry locking lugs 46 and 47. Slidably carried by the overlapped portions of bolts 38 and 39 is a lock block 48 having therein a cylindrical type lock 49 of any suitable make. This cylinder lock is equipped with suitable tumblers adapted to fasten it in required position with respect to block 48, and the rotatable cylinder thereof carries with it a double hook 50. The bolts 38 and 39 are adapted to be forced outwardly by squeezing the straps 42 and 44 toward each other to the closed position shown in Fig. 1, at which time 50 the outermost ends of the respective bolts are adapted to project outwardly beyond the side guides 30, through suitable lock openings (not shown) provided therein, these openings being located to register with the ends of the bolts 55 when the grille is in vertical closed position. When the bolts are thus extended outwardly, the locking lugs 46 and 47 attain a mutually approaching position where they are adapted to be held by the double hook element 50, upon 60 suitable rotation of the lock 49, which latter is adapted to be locked in this position. With such an arrangement any attempt to force the bolts 38 and 39 is exerted against the double hook 50 rather than against the relatively delicate cylinder lock itself. Preferably suitable springs 51 are located between a collar on each bolt and a convenient link 40 so as normally to urge such bolt into its innermost or unlocked position, and the stock of bolts 38 and 39 may 70 be hardened to resist cutting.

In Figs. 11 and 12 an alternative form of locking device is illustrated. Involving bolts 139 and 140 having their inner ends overlapped and relatively confined by straps 142 and 144, each 75

of which is rigidly fastened to one bolt and slidably engaged over the other adjacent bolt. The straps are adapted to be embraced by a padlock, and in operation, when it is desired to lock the grille, the straps 142 and 144 are squeezed together and such a lock is applied thereto to hold them in their mutually juxtaposed position. With this arrangement, the lock may conveniently be swung around to either side of the grille.

A generally similar form of grille, but one which is adapted to be assembled in a somewhat different manner, is illustrated in Figs. 13 to 15. Here, a plurality of laterally extending rods 220 are used, which are adapted to be flexibly interconnected by means of links 221 provided at their ends with eyes 222. These eyes are prevented from slipping along the rods 220 by means of knobs or projections 223. Instead of being pinched or struck up on the rods 220 after positioning of the links 221 thereon, these knobs are preformed upon the rods prior to their assembly with the links. Such knobs are located at suitably spaced intervals along the rod wherever an eye 222 is to be confined and preferably are arranged in diametrically opposed pairs as best shown in Fig. 15. The perforations in eyes 222 are equipped with diametrically opposed keyways or slots 252 which are adapted to be slid over knobs 223 when in registry therewith. In assembling a grille of this type, a given rod may be threaded through a series of notch equipped links, and thereafter given a quarter turn so as to place the knobs 223 and slots 252 out of registry. End links 224, similar to or identical with those previously described, flexibly interconnect the ends of the several rods, and are held against inward sliding movement therealong by means of additional knobs such as 223 or by a suitable collar or shoulder indicated at 253. Outward movement of these links is prevented by a spring wire 254 which runs from the top to the bottom of the grille and is threaded through a suitable opening in the end of each rod. This wire also serves to prevent undue rotation of the rods 220 with respect to the notched eyes 222, and thus precludes undesired registry of the confining knobs 223 and notches 252 after assembly.

Each form of grille herein described is capable of being readily and quickly manufactured, and most of the operations involved in their preparation may be performed on machines. The grilles are readily able to roll up around a horizontal shaft, and may be attached to and suspended from such a shaft in any known or suitable manner, and the shaft may be provided with suitable springs or counterweights, as is readily understood in the art. It will be seen that there has been provided a flexible closure grille which is well adapted to fulfil its intended functions.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the

invention which, as a matter of language, might be said to fall therebetween.

Having described my invention, what I claim as new and desire to secure by Letters Patent, is:

1. A flexible grille comprising a plurality of straight parallel rods, a plurality of spaced links spacing and flexibly interconnecting adjacent rods, said rods having integral projections extending therefrom and respectively confining each link against movement therealong, and additional aligned end links interconnecting and pivotally mounted on the ends of adjacent rods, and vertical guides at the sides of said grille for confining said aligned end links to movement in a vertical path.

2. A flexible grille adapted to be coiled about a horizontal shaft, comprising a plurality of laterally extending rods, links flexibly connecting adjacent rods, means confining said links against movement along said rods, at least some of said links being in vertical alignment, and means on such vertically aligned links for directly compelling alignment between a link connecting two adjacent rods and other aligned links connecting other rods during coiling of the grille.

3. A flexible grille adapted to be coiled about a shaft, comprising a plurality of straight parallel rods, a plurality of links flexibly connecting the intermediate portions of adjacent rods, additional aligned end links flexibly connecting the ends of said rods, and means on said end links directly compelling alignment between a link connecting two adjacent rods and other aligned links connecting other rods during coiling of the grille.

4. A flexible grille adapted to be coiled about a shaft, comprising a plurality of laterally extending rods, means flexibly connecting adjacent rods including a series of links arranged in overlapping end to end relation, each pair of such links having overlapped ends rotatably mounted on one of said rods as a pivot, said overlapped ends being mutually offset with respect to their associated links so that said series of links is arranged in vertical alignment, said links each having an aligning rib and an aligning groove arranged to hold said links in alignment during coiling of the grille.

5. A link for use in a grille having laterally extending spaced rods, comprising a body portion having an aligning rib along one edge and an aligning groove along its reverse edge, and having perforate eyes in its end portions, each eye forming a pivotal bearing for one of said rods.

6. A link for use in a grille of the class described, comprising a body portion having an aligning rib along one edge and an aligning groove along its reverse edge, and having perforate end portions, said portions being mutually offset on opposite sides of a longitudinal axis of said link.

7. A flexible roll-up grille for doorways, comprising a plurality of straight parallel rods having knobs projecting therefrom, a plurality of links flexibly connecting adjacent rods, said links having perforate eyes equipped with slots enabling them to be slid over said knobs when in registry therewith, said knobs serving to confine said links against movement along said rods when in non-registry with said slots, and means for holding said knobs and slots out of registry in the assembled and operative condition of the grille.

8. A flexible grille, comprising a plurality of straight parallel rods having knobs projecting therefrom, a plurality of links flexibly connecting adjacent rods, said links having perforate eyes equipped with slots enabling them to be slid over said knobs during assembly of the grille, said knobs serving to confine said links against movement along said rods when in non-registry with said slots, and a continuous flexible wire passing through said rods for holding said knobs and slots out of registry in the assembled condition of the grille.

9. A flexible grille comprising a plurality of laterally extending rods, a plurality of links flexibly connecting adjacent rods, a pair of laterally extending locking bolts located between a pair of said rods and slidably mounted in the links extending therebetween, said bolts extending from side to side of said grille, and being formed of stock resembling said rods in appearance, and means for projecting the outer ends of said bolts beyond the sides of the grille for locking purposes.

10. A flexible grille comprising a plurality of

laterally extending rods, a plurality of links flexibly connecting adjacent rods, a pair of laterally extending locking bolts slidably mounted in the links connecting an adjacent pair of said rods, said bolts having their inner ends overlapped and having their outer ends adapted to project beyond the sides of the grille for locking purposes when such inner ends are moved toward each other, and means for holding the inner ends of said bolts in mutually juxtaposed relation.

11. A flexible grille comprising a plurality of laterally extending rods, a plurality of links flexibly connecting adjacent rods, a pair of laterally extending locking bolts slidably mounted in the links connecting an adjacent pair of said rods, said bolts having their inner ends overlapped and each carrying a locking lug, a rotatable cylinder lock mounted between said lugs and carrying a double hook element therewith, said hook element being adapted to be rotated to engage and confine said lugs upon mutual approach of the latter.

MILTON L. CORNELL.
